J. BENSON

DRILL RECOVERY TOOL FOR DEEP WELLS

Filed May 12, 1923

BY

Arthur W. Nelson

ATTORNEY.

UNITED STATES PATENT OFFICE.

JOHN BENSON, OF WEST CHICAGO, ILLINOIS.

DRILL-RECOVERY TOOL FOR DEEP WELLS.

Application filed May 12, 1923. Serial No. 638,561.

To all whom it may concern:

Be it known that I, JOHN BENSON, a citizen of the United States, and a resident of West Chicago, county of Du Page and State 5 of Illinois, have invented certain new and useful Improvements in Drill-Recovery Tools for Deep Wells, of which the following is a specification.

This invention has for its object to provide 10 a drill-recovery tool for deep-wells for salvaging detached or broken drills.

The particular objects of the invention are:—

First. To provide a recovery device of 15 this general character which will permit the operator to determine in advance the exact point between the ends of the drill point, including both the head and shank thereof, at which the same shall be engaged by the recovery tool.

Second. To provide simple and efficient means for manually effecting release of the drill from the recovery-tool after recovery of the drill.

Third. To provide means for initially positioning the active drill engaging elements of the recovery tool with respect to the diameter of the part of the drill to be recovered in order to effect engagement thereof 20 with the drill at said point, and further to provide a relatively wide range of adjustment of said active elements so as to adapt a single recovery tool to be used for recovering tools of various sizes.

Fourth. To provide a single element for effecting both aforesaid adjustments of the active drill engaging elements.

Other objects and advantages of the invention will be fully explained in the following 40 specification.

The preferred embodiment of the invention is illustrated in the accompanying drawings wherein Fig. 1 is a central longitudinal section of a drill recovery tool constructed 45 in accordance with the invention.

Fig. 2 is a transverse section of the same on the line 2—2 of Fig. 1; and

Fig. 3 is a detail perspective view of a grab expanding key employed.

Deep well drills are made in a great variety of different designs with respect to the shanks thereof, the heads being generally cylindrical and relatively short. If the tool becomes detached from the drill rod or the shank thereof is broken, the well driller 55 knows from the part recovered with the

drill-rod the most advantageous point at which to grab the remaining portion of the tool in the well. Accordingly, by determining the distance between the uppermost end of the broken or detached shank of the tool and the point at which he desires to grab the same, the well-driller can determine the distance between the grabs of the tool and the upper end of the hollow or bore thereof so as to effect projection of the shank into said bore or hollow the exact distance required to effect engagement of the grabs with that portion of the shank or head of the drill which he desires to engage. There is also some difference in diameters of the shanks of drills which the driller must take into account when endeavoring to recover the drill.

The tool of the present invention consists essentially of a shank 1 of such length and general shape as may be adapted for engagement in the end or chuck of the drill-rod employed, the lower end 2 of said shank or tool-head constituting a stop against which the upper end of the shank of the drill is adapted to abut. The lower end portion of said shank or tool-head 1 is externally threaded and is preferably provided with an externally threaded annularly reduced portion 3, at its lower end upon which the upper end of the section 4 of ordinary pipe is adapted to be mounted. Said pipe-section 4 is also preferably threaded externally at its upper and lower end portions. The upper end portion thereof is adapted to be engaged by the internally threaded sleeve 5 which also has threaded engagement with the larger portion of said shank or tool head 1.

Threaded upon the lower end portion of the pipe section 4 is the grab containing portion or grab-head 6 of the tool which is internally threaded at its upper end portion to receive said pipe section 4, the latter being preferably held against rotation relatively thereto after being mounted thereon by tapping holes 7 into the threaded portion of the pipe section to receive a set screw 8.

The grab-head 6 is cylindrical externally, and below the threaded portion thereof the circumferential wall thereof is preferably gradually increased in thickness to the lower end of the same, the lower edge of said wall being bevelled as indicated at 9 so as to provide a sharp outer cutting edge, said bevelled edge being also adapted to guide the extreme upper end of the drill into said head 6.

Between its ends, said head 6 is provided

internally with an annular tapered groove 10 converging toward the lower end or bevelled edge of said portion 9, the greatest depth of said groove 10, being such, with reference to the angularity of the bevel, as may be best adapted to the purpose of its use. Mounted within said bevelled groove 10 is the grab-element 11 which consists of a split ring having, preferably, a cylindrical inner face and a tapered or bevelled outer face, corresponding preferably with the bevel of the groove 10. Said grab 11 is preferably composed of steel or other suitable material having some resiliency so that it may be contracted and expanded by moving it longitudinally of the head 6, by engagement of its outer face with the opposed face or wall of the groove 10. The upper end of the pipe-section 4 constitutes a means for forcing said grab 11 downwardly toward the mouth of the head 6 in order to contract it to the degree necessary to effect engagement with that portion of the drill to be recovered which it is desired to engage. The inner cylindrical face of the grab is provided with a plurality of inwardly projecting toothed or serrated surfaces 12 which are adapted to bite into that portion of the surface of the drill-shank or head adapted to be engaged, the said teeth having their bevelled surfaces extending toward the mouth of the head 6 as is common in the art. The open space between the ends of the said grab 11 is disposed so that the walls thereof project into the area of the opening 13 in one side of the head 6, through which the cross-head 14 of a key 15 is adapted to be inserted, the smaller lateral dimension of said end portion 14 of said key being less than the width of said open space in the grab so that by inserting and rotating said key on its own axis said head 14 will act as a wedge to effect expansion of said grab to thereby release it from engagement with the tool.

After the serrated surfaces of the grab have engaged the tool, the weight of the latter plus the resistance to raising the same occasioned by friction or its becoming wedged in the bore of the well, will obviously tend to effect a downward movement of the grab 11 relatively to the head 6, thus effecting a further contraction of said grab 11 and a correspondingly tighter hold on the surface of the tool. The expansion of the said grab by means of the key will obviously tend to effect its upward movement relatively to the head 6 at the same time that it effects release of the serrated surfaces from the surface of the tool engaged thereby. The length of the pipe section 4 will be determined by the distance between the stop 2 and the grab 11 which will determine the point at which the grab is adapted to engage the tool. Obviously in this way the tool

may be cheaply and easily made of any desired length.

In the event that the well should contain water it is preferable to provide the pipe-section 4 with a plurality of openings 16 to facilitate its engagement with the drill point to be recovered.

While I have shown the preferred embodiment of the invention in the drawings, it will be understood, of course, that the same may be varied in details of construction to adapt it to any particular type or style of drill point to be recovered and to the particular conditions appertaining to the well, without departing from the invention as defined in the appended claims.

I claim as my invention:

1. A drill recovery tool including a grab-head, an elastic one piece split ring loosely disposed within the same, grab elements associated with said split ring, the latter and said head having coacting means for effecting contraction of said ring to cause said grab elements to engage a drill to be recovered, and manually operable means for effecting forced expansion of said ring to effect disengagement of said grab elements from the recovered drill.

2. A drill-recovery tool including a grab-head, an elastic one piece split ring, grab-elements carried thereby, a carrier for said grab-head, a sleeve connecting the latter with said carrier and detachably engaged with said head and said carrier, the lower end of the latter constituting a stop formation for limiting the projection of the drill to be recovered into said recovery tool to thereby determine the point between the ends of the drill to be engaged by said grab-elements, the length of said sleeve determining said point.

3. A drill-recovery tool including a hollow grab-head, a one piece split ring, grab elements operatively associated therewith, a stop associated with the grab-head for determining the point in the drill to be recovered for engagement of the grab elements therewith, and means for varying the distance between said grab-elements and said stop.

4. A drill-recovery tool including a grab-head, a one piece split ring having grabs operatively associated therewith, movable longitudinally of the grab-head to thereby effect relative radial movement of said grabs, and including means for normally maintaining said grabs at one limit of movement relatively to said head, and means for forcibly maintaining said grabs normally disposed at any desired point between the limits of their movement relatively to the head to thereby adjust their position therein with respect to the diameter of the surface to be engaged by said grabs.

5. A drill-recovery tool including a grab-

head, a one piece split ring having grabs operatively associated therewith, movable longitudinally of the grab-head to thereby effect relative radial movement of said grabs, and including means for normally maintaining said grabs at one limit of movement relatively to said head, means for forcibly maintaining said grabs normally disposed at any desired point between the limits of their movement relatively to the head to thereby adjust their position therein with respect to the diameter of the surface to be engaged by said grabs, and a carrier for said grab-head, said last-named means constituting a coupling connecting said carrier with said grab head.

6. A drill-recovery tool including a grab-head, a one piece split ring having grabs operatively associated therewith, movable longitudinally of the grab-head to thereby effect relative radial movement of said grabs, and including means for normally maintaining said grabs at one limit of movement relatively to said head, means for forcibly maintaining said grabs normally disposed at any desired point between the limits of their movement relatively to the head to thereby adjust their position therein with respect to the diameter of the surface to be engaged by said grabs, and a carrier for said grab-head constituting a stop adapted to be engaged by the drill to be recovered for determining the portion of the surface thereof to be engaged by said grabs, said last-named means constituting a coupling connecting said carrier with said grab-head and further constituting means for determining the distance between said grabs and said stop.

40 7. A drill recovery tool including a grab-

head, a one piece split ring having grabs carried thereby movable longitudinally and radially of the grab-head, and including means for normally maintaining said grabs disposed at their uppermost and outermost limits of movement relatively to said head, a sleeve adjustably associated with said head in engaging relation to said grabs for forcibly holding the same at a predetermined point between the limits of their movement relative to the head to thereby determine their position with respect to the diameter of the surface of the drill to be engaged thereby, and a stop in the sleeve for determining the point between the ends of the drill to be recovered to be engaged by said grabs.

8. A drill recovery tool including a grab-head, a one piece split ring having grabs carried thereby movable longitudinally and radially of the grab-head, and including means for normally maintaining said grabs disposed at their uppermost and outermost limits of movement relatively to said head, a sleeve adjustably associated with said head in engaging relation to said grabs for forcibly holding the same at a predetermined point between the limits of their movement relative to the head to thereby determine their position with respect to the diameter of the surface of the drill to be engaged thereby, and a stop in the sleeve for determining the point between the ends of the drill to be recovered to be engaged by said grabs, and manually operable means for effecting release of said grabs from the recovered drill.

In testimony whereof, I have hereunto set my hand, this 9th day of May, 1923.

JOHN BENSON.
